JOHN WOLF, OF TOPEKA, KANSAS.

LOCK.

1,310,775.

Specification of Letters Patent. Patented July 22, 1919.

Application filed May 8, 1919. Serial No. 295,584.

To all whom it may concern:

Be it known that I, JOHN WOLF, a citizen of the United States, residing at Topeka, in the county of Shawnee and State of Kansas, have invented certain new and useful Improvements in Locks, of which the following is a full, clear, and exact description, reference being had to the accompanying drawings, forming a part hereof.

10 The present invention is directed to improvements in locks, and more particularly to that type of lock adapted to be used on wardrobe trunks. The object of the invention is to provide a locking device consisting 15 of a key-lock and a complementary lock or latch coöperating with it. A further object is to provide coöperating locks, the operating mechanism of the one being inaccessible until the other is opened; to provide a lock 20 that can not be "forced" open without destroying the trunk; to provide a locking device that is positive in its action, quickly and easily operated, and one possessing further and other advantages more fully set forth in 25 the following detailed description in connection with the accompanying drawings in which—

Figure 1 represents a front elevation of a trunk with my invention applied thereto; 30 Fig. 2 is a top plan of the upper lock with the hinge leaf swung open and broken at the middle; Fig. 3 is a side elevation of the upper lock with the trunk wall in section; Fig. 4 is an enlarged horizontal section on the 35 line 4—4 of Fig. 1; Fig. 5 is a detached bottom plan of the upper key-lock and bottom latch-lock with their connecting rod, the hinge leaf of the upper lock being swung open; Fig. 6 is a top plan of the bottom 40 latch-lock swung to open position; Fig. 7 is an enlarged vertical longitudinal section on the line 7—7 of Fig. 1 with parts broken away; Fig. 8 is a horizontal cross-section on the line 8—8 of Fig. 1; Fig. 9 is an enlarged 45 vertical cross-section on the line 9—9 of Fig. 1; Fig. 10 is a top plan of the socket of the socket member of the bottom latch-lock showing the circumferential slit thereof, the socket being broken at the middle; and Fig. 50 11 is an elevation of the part shown in Fig. 10.

Referring to the drawings, 1 and 2 represent the respective halves or hinged sections of an ordinary wardrobe trunk, the same 55 coming together along the seam or joint a, which is protected by the valance 3 secured

to the section 2, as well understood in the art. L represents the upper key-lock and L' the bottom latch-lock. The key-lock comprises a socket member 4 secured to the trunk section 60 1, and a coöperating member composed of a plate 5 secured to the trunk section 2 and a locking member or leaf 6 hinged to said plate. The latch-lock L' comprises a socket member 4' secured to the trunk section 1, and 65 a coöperating member composed of a plate 5' secured to the section 2 and a locking member or leaf 6' hinged to said plate 5'.

The detailed construction of the key-lock L is substantially as follows: The member 6 70 is secured to the plate 5 by a hinge pin 7. Mounted on the under side of the hinged member or leaf 6 is a cylinder-lock C of any approved type (Yale, Corbin, or the like) the latch-bolts 8, 8, whereof when the leaf 75 is swung to closed position, snap into the openings o, o, formed for their reception in the wall of the socket 9 of the member 4 (Fig. 3), the wall of the trunk section 1 being provided with an opening B for receiving 80 said socket. Obviously, in order to close the locking leaf 6 into the socket 9 the two trunk sections 1, 2, must first be closed (Fig. 1), the swinging of the section 2 against the section 1 causing the tongues t on the plate 85 5 mounted on the trunk section 2, to enter the recesses r, r, formed in the socket member 4 on the trunk section 1. Obviously the positions of the tongues t and recesses r might be reversed without affecting the nature of 90 the invention. Secured to the under side of the leaf 6 is one end of a flexed spring 10 which for a closed position of the leaf is under tension, so that upon the release of the leaf by unlocking the lock C, the 95 spring will force the leaf to open position (shown dotted in Fig. 4). The plate comprising the socket member 4 is provided with an opening O elongated in a direction parallel to the hinge axis of the leaf 6, the purpose 100 of which opening will presently be seen.

The latch-lock L' is likewise provided with a socket member 4', a plate 5' and locking leaf 6' hinged to the plate 5', a spring 10' secured to the leaf 6', tongues t', and recesses 105 r', all operating substantially as the corresponding parts of the key-lock L. The manner of securing the plate or socket-member 4' to the wall of the trunk section 1 is substantially the same as that of securing the 110 socket member or plate 4 of the key-lock L. In lieu of a cylinder lock such as C, the latch-

lock L' is provided with a cylindrical member 11 mounted on the under side of the leaf 6', the inner end of the cylinder when the leaf 6' is closed extending just inside the 5 plane of the inner surface of the wall of the trunk section 1 (Figs. 8, 9). Secured to the inner end of the cylinder is a casing 12 in which is slidably mounted a latch-bolt 13, said bolt being provided with a headed stem 10 14 about which is coiled a spring 15, one end of the spring engaging the wall of the casing 12 and the other bearing against the bolt, whereby the latter is normally forced outward, the bolt as well as its stem operating loosely through suitable openings in 15 the casing walls, the stem terminating in a beaded head *w* to prevent the stem from being forced by the spring 15 out of the opening in the casing wall in which it operates. 20 Mounted inside the trunk and held in place by the guides or straps *g* secured to the walls of the trunk is a pull rod 16, the upper end of the rod or that adjacent the key-lock L terminating in an outwardly projecting lug 25 17 to which is pivotally secured the forked end of a finger-hold or lever 18, the rod terminating opposite the opening O of the socket member 4, and the registering opening O' formed in the trunk wall, the connection 30 between the members 17 and 18 being effected through said openings. This leaves the lever 18 on the outside of the socket member 4 and the trunk wall, the rod 16 being on the opposite (inside) side of said members. It will be seen from Fig. 4 that 35 when the leaf 6 is closed, the lever 18 is inaccessible so that the rod 16 can not be manipulated. The end of the rod adjacent the latch-lock L' is provided with a laterally 40 projecting keeper arm 19, the same being adapted to operate in a peripheral circumferential slit *s* in the wall of the socket 9' of the socket member 4'. When the leaf 6 of the key-lock is closed the bottom edge *e* 45 of the keeper arm 19 is substantially at the bottom of the slit *s* (Fig. 5), the rounded surface *a* of the bolt 13 (Fig. 9) freely riding over the edge *e* with a closing movement of the leaf 6', thereby permitting the spring 50 15 to be compressed, and when the free end of the bolt has passed off said edge *e* the spring causes the bolt to spring behind the keeper, thereby locking the leaf 6' thereto, the bolt being arrested by the offset or shoulder *m* striking the edge of the keeper (Fig. 55 9). The parts referred to are protected by a cover or casing P, a suitable recess *n* (Fig. 7) being formed in the wall thereof for the free passage therethrough of the rod 16. 60 The lower end of the rod 16 terminates in a lug 20 substantially even with the edge *e* of the keeper 19 (Figs. 5, 7,) said lug having extending upwardly therefrom and terminating in the peripheral wall of the cover 65 P, a rod or stem 21, said stem being loose in both the lug 20 and wall of the cover P, and terminating in expanded heads to keep the same in place. Coiled about the stem is a spring 22 one end of which bears against the lug 20, the opposite end bearing against 70 the wall of the cover P acting as an abutment.

To open the trunk, the key-lock L is first unlocked in the usual way and the leaf 6 swung open. This exposes the handle or 75 lever 18 by which the rod 16 may now be lifted or pulled up, a sufficient lift causing the keeper 19 to be pulled out of engagement with the latch-bolt 13. The latch-bolt 13 being released leaves the flexed spring 10' 80 free to force the leaf 6' to open position (dotted position Fig. 8). With the lifting of the rod 16 the spring 22 is necessarily compressed, so that upon release of the rod it immediately resumes its normal position 85 for subsequent coöperation with the latch-bolt 13 when the leaf 6' is swung to closed position.

It will be seen from the foregoing that 90 the latch-lock L' can not be manipulated or opened until the key-lock L is unlocked, access to the handle 18 by which the pull rod 16 is lifted being had only upon the opening of the leaf 6 of the key-lock, said leaf covering the handle and the upper end 95 of the pull rod when the leaf is closed and locked. The provision of the slot O in the plate or socket member 4 of the lock L constitutes one of the novel features of the present invention, said slot making it possible 100 to gain access to the rod 16 on the inside of the trunk and manipulate the same to release the keeper 19 from the latch-bolt 13, whereupon the spring 10' automatically 105 forces the leaf 6' to open or unlocking position, permitting the opening of the trunk or parting of the sections 1, 2. Obviously, the locks need not be limited in their application to trunks, but may be applied to any 110 receptacle or container, or in any relation where access to the operating elements of one lock may be had only through the unlocking of the other lock; or where access to the operating elements of one lock must be had through one of the sections or members 115 of the opposite lock upon the unlocking of a complementary section of such opposite lock. In the present example the socket member or section 4 of the lock constitutes 120 the direct means of access through the opening O to the operating element 16 of the other lock, when the section or leaf 6 has been unlocked and swung to open position to expose the lever 18 by which the rod 16 is manipulated. In the example before us 125 the trunk section 1 may be considered as the stationary section and the section 2 as the movable or hinged section, though as a matter of fact both are in a sense movable relatively to one another. In other cases, 130

as in vaults, safety boxes and the like, only one wall (the door) is movable, the wall to which the door is locked being stationary. For convenience we may consider the plates 5 or lock members or sections 4, 4', as the stationary sections, and the plates 5, 5', with their leaves 6, 6', as the movable sections of the respective locks. By way of further analysis, it will be observed that the bolt 13 moves in a plane across the axis of the socket 9', as does also the keeper 19. The details of the locks may be changed without involving a departure from the nature or spirit of the invention.

Having described my invention what I claim is:

1. In a latch-lock of the character described, a socket member, a leaf hinged thereto, a spring-controlled latch-bolt carried by the leaf and confined in the socket of the socket member for a closed position of the leaf, said latch-bolt being reciprocable across the axis of the socket, a circumferential peripheral slit being formed in 25 the socket wall to one side of the locking face of the latch-bolt, a keeper member movable through the slit to and from the socket axis and into engagement with the locking face of the latch-bolt, a rod secured to the 30 keeper, and a spring for normally forcing the rod and the keeper into locking position with the latch-bolt, the parts operating substantially as, and for the purpose set forth.

2. In combination with a trunk provided 35 with two sections in hinged relation and abutting with their free edges for a closed position of the trunk, a lock comprising a

socket member on one section and a hinge-leaf on the opposite section adapted to enter the socket of said socket member, a latch-lock removed from the first mentioned lock and comprising a socket member on one of the trunk sections and a hinge-leaf on the opposite section adapted to enter the socket of the socket member, a latch-bolt on the hinge-leaf, the socket members and hinge-leaves of the respective locks being disposed on corresponding sections of the trunk, a keeper, and an operating rod on the inside of the trunk 50 leading from the keeper to the first mentioned lock, the socket member of the first lock and the trunk wall being provided with a common opening through which the rod may be seized from a point outside the 55 socket-member aforesaid with an opening of the leaf locked thereto, and the latch-lock unlocked by a movement of the rod in proper direction.

3. A latch-lock provided with a socket 60 having a circumferential peripheral slit in the walls thereof, a hinge-leaf adapted to enter said socket, a keeper traversing said slit, a bolt mounted on the under side of said hinge-leaf and adapted to engage the 65 keeper when said hinge-leaf is in the socket, and means for withdrawing the keeper from said bolt.

In testimony whereof I affix my signature, in presence of two witnesses.

JOHN WOLF.
